UNITED STATES PATENT OFFICE.

ANNA M. DANDO AND FRANK H. STAIR, OF SCRANTON, PENNSYLVANIA.

MINER'S SAFETY-LAMP.

SPECIFICATION forming part of Letters Patent No. 700,407, dated May 20, 1902.

Application filed July 18, 1900. Serial No. 24,117. (No model.)

To all whom it may concern:

Be it known that we, ANNA M. DANDO and FRANK H. STAIR, citizens of the United States, residing at Scranton, in the county of Lackawanna and State of Pennsylvania, have invented certain new and useful Improvements in Miners' Safety-Lamps, of which the following is a specification, reference being had therein to the accompanying drawings.

10 This invention relates to miners' safety-lamps, and has for its objects to provide a simplified and more efficient magnetic locking device for such lamp and otherwise constructing such lamp so as not to be interfered with by unauthorized persons, whereby mining disasters by explosion might result.

To this end our invention consists of the construction, combination, and arrangement of the several parts, as herein described and 20 illustrated in the accompanying drawings.

Referring to the drawings, Figure 1 is a side elevation of the bowl of one of our improved lamps having the top removed. Fig. 2 is a top plan view of the said bowl. Fig. 3 is an 25 under side view of the same. Fig. 4 is a view in cross-section taken on the lines *x y* of Figs. 2 and 3. Fig. 5 is a detail view of a plug used in the locking device. Fig. 6 is a detail view of the armature used in the locking device. 30 Fig. 7 is a view of our lamp complete, sitting in the relation with an electrical magnet as required to unlock the bowl from the top portion of the lamp.

Similar characters of reference denote like 35 and corresponding parts throughout the several views.

In the drawings, 1 designates the main body of the bowl of one of our lamps, which is constructed from brass or other suitable material. 40 It is provided with a screw-thread 2, by means of which it is to be securely attached to the upper portion 3 of a miner's lamp of any usual construction.

Our lamp is provided with a peculiar-shaped 45 wick-tube 4, having a screw-threaded connection 5 at the center of the top of the bowl and provided with a thumb-screw 6, by means of which it may be inserted and removed after the wick has been inserted into the interior 50 of the tube. The upper portion of the wick-tube is plain and has sliding over it a sheath 7, which is integrally made with a screw-

threaded lug 8, having a screw-threaded connection with the threaded shank 9 of the pin 10, extending upward through a tube or covering 11 in the interior of the bowl. This pin is provided with a collar 12, which prevents it from sliding downward through the bowl, and is provided at the opposite end with a thumb-button 13, which is secured thereto after the pin 10 is inserted downward through the tube 11 of the lamp-bowl. By this arrangement the sheath 7 is adapted to be raised and lowered on the wick-tube 4 by turning the thumb-button 13 to the right or left, as required, the object being to vary the light produced and to have the variation limited to such an amount as is thought requisite by the authorities having the care of the lamp. An additional tube 14 extends vertically up through the bowl of the lamp and is provided with a revolving pin 15, also provided with a thumb-button 13' on the lower end and a serrated disk 16 on the upper end. Parallel to the upper end of this tube and in proximity to the serrated disk is a match-holding receptacle 17, which is adapted to hold 75 an explosive match adapted to be set off by turning the button 13, so as to cause the serrated disk 16 to grate upon the head of the match, thus forming a lighting device in order to light the wick in the tube 4 without 80 the necessity of unscrewing the bowl 1 from the body 3 of the lamp.

The bowl is locked to the body of the lamp as follows: A sliding pin 18 has its projecting end 19 extending upward through the shoulder of the bowl in proximity to the thread 2. This pin is slideable vertically and is held to the upper part of its course by means of a coiled spring 20, impinging on the collar 21 and seated on the removable plug 22, the 95 lower end of said pin being provided with an armature 23, which armature is incased in a brass or other suitable inclosure 24, so as to be protected from view and interference by the hand of any unauthorized person. The pin 20 is secured into the embossment 25 of the armature by a screw-threaded connection at 26, and the armature, which is of course slideable upward and downward within its in-

casement 24, may be attracted downward, depressing the end of the pin 19 below the surface of the shoulder of the lamp by means of an electromagnet 27, mortised or secured 5 into the top of a table 28 or other suitable place upon which to set the lamp when it is desired to unlock it.

The operation of the parts of our lamp are easily understood. The interior of the bowl 10 of the lamp is filled with suitable oil, and a wick is secured in the tube 4 and extending outward at the top the maximum amount which is allowed for the lamp. This is done by an authorized person before the lamp is 15 placed into the hands of a miner. A match is inserted into the receptacle 17, and the sheath 7 is adjusted downward, so that the wick is exposed about the top of the tube 4, the tube 4 having been previously screwed down to 20 its proper limit into its place in the top of the bowl. The top part of the lamp is now screwed to the bowl the same as in any usual lamp of the kind; but it must be noted that a recess 29 is provided in the metal of the rim 25 30 of the lamp, which recess is adapted to receive the end 19 of the sliding pin 20 when the bowl is fully screwed home, the body of the lamp being turned in the process of securing the bowl to it in the direction of the 30 arrow in Fig. 7, the rim 30 pressing the pin downward until the recess 29 reaches it, when the pin snaps into its place. It is evident that all that is necessary to do in unlocking the lamp is to set it on a table 28, with the 35 armature 23 over a magnet 27, which electromagnet is to be strong enough to overcome the tension of the spring 18, so as to draw the pin down until the end 19 is withdrawn from the recess 29, when, of course, the lamp can be

unscrewed in the usual way. This electromagnet, if desired, may be kept a secret from the miners using the lamp, who do not need to know, if thought best, where or how the lamps are unlocked or why they unlock when placed upon a certain table. 40 45

Having thus described our invention, what we claim, and desire to secure by Letters Patent, is—

The herein-described magnetic locking device for miners' lamps consisting in combination with the bowl of said lamp, of a chamber in one side of said bowl, a spring-controlled sliding pin within said chamber, one end of said pin projecting upward and arranged to engage with a recess in the body 50 of the lamp to which the said bowl is to be attached for the purpose of locking it thereto, and the other end of said pin provided with a comparatively large-sized armature lengthened so as to cover both poles of a horseshoe-magnet and slidable within the chamber, the bottom of said chamber provided with a suitable closure, whereby the sliding pin may be drawn downward by the action of an electromagnet when the lamp is placed in close relation to such magnet, for the purpose of disengaging the locking device, and at the same time preventing any physical contact with the armature or pin from without, substantially as specified. 55 60 65 70

In testimony whereof we affix our signatures in presence of two witnesses.

ANNA M. DANDO,
FRANK H. STAIR.
